(57) **CLAIM**

The ornamental design for a liquid scent dispenser, as shown and described.

DESCRIPTION

FIG. 1 is a perspective view of a liquid scent dispenser showing our new design;

FIG. 2 is a side view thereof;

FIG. 3 is another side view thereof;

FIG. 4 is a bottom view thereof; and,

FIG. 5 is a top view thereof.

The broken lines immediately adjacent the shaded surfaces represent the bounds of the claimed design. All other broken lines depict environmental subject matter that forms no part of the claimed design.
